UNITED STATES PATENT OFFICE.

DONALD HENRY MITCHELL, OF CHATTANOOGA, TENNESSEE, ASSIGNOR OF ONE-HALF
TO HARLEY A. W. HOWCOTT, OF NEW ORLEANS, LOUISIANA.

AUTOMATIC EXPANDING OIL DRILL.

Application filed October 22, 1923. Serial No. 670,170.

To all whom it may concern:

Be it known that I, DONALD H. MITCHELL, a citizen of the United States of America, residing at Chattanooga, in the county of Hamilton and State of Tennessee, have invented certain new and useful Improvements in Automatic Expanding Oil Drills; and I do hereby declare that the following is a full, clear, concise, and exact description of the invention, such as will enable others skilled in the art to which it appertains to make and use the same.

This invention relates to improvements in rotary drills, having for an object to provide an automatic expanding rotary oil well drill capable of being operated by either the drill stem or casing of well drilling rigging and which, when in operation, will positively prevent disengagement of the cutters or reamers, the drill being automatically locked to the casing or stem and when desired, may be readily disconnected therefrom in order that it may be withdrawn from the bore without necessity of removing the drill stem or casing.

It is also an object of the invention to provide the drill with novel forms of automatically operable locking devices for connecting the drill to a casing or stem and for securing the drill body in a fixed position with respect to the casing or stem in order that the cutters or reamers will be rigidly retained in extended operative positions, but which, with disengagement of their locking means, may be moved to retracted or inoperative positions to allow withdrawal of the drill from such casing or stem.

It is likewise an object of the invention to provide a drill body having the upper portion of the drill so formed as to permit of its driving connection to a casing or stem, thus allowing of the transmission of rotary motion thereto.

Another and equally important object of the invention may be stated to reside in providing the drill with an over-shot device which when lowered into engagement with the drill will serve to automatically release the locking means and simultaneously be automatically connected to a portion of the drill whereby the same may be elevated from the casing or stem and thus, removed from the bore for various purposes.

Yet another object of the invention is to

provide a drill having the so-called rock rollers or cutters mounted thereon in a manner such as will permit the same to effectually cut through either rock or earth or mud, such cutters having means on the same which will prevent the passage of grit or sand into engagement with their bearing surfaces and causing premature deterioration of the same.

A further object of the invention is to provide the drill with novelty arranged water ways or ducts adapted to convey and discharge water onto the cutters of the drill during their operation whereby to cool the same.

A still further object of the invention is to provide the drill with cutting and reaming devices which when in operation will serve to effectually cut the dirt or mud and then plaster or smooth the walls of the bore or hole.

Other objects will be in part obvious and in part pointed out hereinafter.

In order that the invention and its mode of operation may be readily understood by persons skilled in the art, I have in the accompanying illustrative drawings, and in the detailed following description based thereon, set out one possible embodiment of the same.

In these drawings:

Figure 1 is a side elevation of the improved drill;

Figure 2 is a fragmentary side elevation thereof, taken at substantially right angles to the Figure 1;

Figure 3 is a longitudinal section through the improved drill;

Figure 4 is a similar section taken on the line 4-4 of Figure 3;

Figure 5 is an enlarged fragmentary longitudinal section through the drill and the over shot grapple device, showing the manner in which this latter device is adapted to be connected to the drill;

Figure 6 is a detail in perspective of the lower portion of the slide bar;

Figure 7 is a disassembled fragmentary detail in perspective showing the manner in which the clamping bars are connected to the lateral extensions of the lower portion of the slide bar;

Figure 8 is a detail, partly in section of the form of cutter employed;

2
Figure 9 is a side elevation of the form of reamer;

Figure 10 is a front elevation of the same;

Figure 11 is a transverse section taken on the line 11—11 of Figure 9;

Figure 12 is a similar view taken on the line 12—12 of Figure 9;

Figure 13 is a transverse section through the lower portion of the drill body; and;

Figure 14 is a fragmentary detail in section showing the mounting of the cutter elements upon the drill head and cutters.

Having more particular reference to the drawings, in connection with which like characters of reference will designate corresponding parts throughout, the improved drill may be stated to comprise a body portion indicated in its entirety by the numeral 1, the upper portion of which is formed 15 hexagonal or similarly shaped, as indicated at 2, while the lower portion thereof is reduced and cylindrical, as indicated at 3; a longitudinally disposed upwardly opening way 4 being formed in the drill body 1 having the lower portion thereof enlarged as indicated at 5 and formed with diametrically disposed substantially rectangularly shaped openings 6. The lower portion or end of the drill body 3 is provided with a screw threaded 25 pocket adapted to be engaged by a drill bit, hereinafter more fully described.

Slidably received in a portion of the longitudinal way 4 is a slide rod 7 having a screw threaded pocket formed in the upper end thereof whereby to receive the screw threaded lower end of a reduced rod 8 passing through an opening formed in the web or shoulder portion 9 within said way 4 and having engagement at its upper end with an 30 enlarged rod 10, the upper end of which extends for a distance above the drill body 1 and is provided with notches or teeth 11 in its opposite sides. An expansible coiled spring 12 is arranged about the reduced rod 10 and has bearing at one end upon an adjacent portion of the web or shoulder 9, while its remaining end bears upon the adjacent end of the slide rod 7. Thus, it will be understood that the spring 12 will normally 35 exert a downward thrust upon the slide rod 7 and in consequence, will serve to normally retain the rod 10 in its lowermost position.

The upper or enlarged portion of the drill body 1, as heretofore stated, is hexagonal or similarly shaped and is adapted to be snugly received in the lower end of a correspondingly shaped drill stem 13 commonly used in connection with oil well drilling rigging.

In order that the enlarged hexagonal portion of the drill body 1 will be positively locked with respect to the lower end of the drill stem 13 and in consequence, will permit the transmission of rotary drilling motion thereto, diametrically positioned bolts

14 are slidably mounted in the upper part of said portion 2, as shown in the Figures 3 and 5 and are normally thrust outwardly by means of expansible coiled springs 15 engaged about the inner portions of the same 70 and having their inner ends resting upon shoulders 16 formed adjacent the openings receiving such bolts. Levers 17 are mounted within a pocket 18 formed in the upper portion 2 of the drill body 1 in proximity to the inner ends of the several bolts 14 and are connected thereto, so that with movement of the same in one direction, inward pulls will be imparted to their respective bolts 14, thus drawing the same to retracted positions 80 with respect to the upper portion 2 of the drill body. The outer ends of these bolts 14 are adapted to be engaged, at times, in keepers or pockets 19 formed at diametrically opposite points within the drill stem 13 and hence, it will be understood that with engagement of the outer ends of the bolts 14 therein, a locking connection as between the drill body 1 and said drill stem 13 will be effected. However, when the bolts 14 are moved to their retracted positions, these pockets 19 will be disengaged and in consequence, connection between the drill body and the drill stem will be interrupted and therefore, relative movement as between the 95 two elements will be permitted.

As additional means for effecting the locking connection between the drill body 1 and the drill stem 13, diametrically disposed pins 20 having rounded heads formed on their outer ends are slidably mounted in pockets provided therefor in the portion 2 of the drill body 1 and are normally thrust outward through the medium of expansible coiled springs 21 arranged thereabout and having certain of their ends bearing upon shoulders formed in said pocket, as shown in the Figure 3. Complementally formed recesses or pockets are formed in adjacent portions of the drill stem 13 and in consequence, with alignment of the same with the rounded heads of the pins 20, said pins will be permitted to enter the same and thereby afford additional connection between the drill body and the drill stem.

Vertically slidable pins 22 are mounted in the upper end of the portion 2 of the drill body 1 upon the opposite sides of the rod 10 and carry wedge-shaped shoes 23 upon their lower ends; these pins being normally held in their uppermost positions by means of expansible coiled springs 24 received about the reduced lower ends of said pins 22 and in the pockets receiving the same, the lower ends of said springs having bearing upon the flanged or shouldered portions of the pockets for the pins 22.

With a view towards providing means for engaging the drill body 1 and removing the same, at times, from the drill stem 13, I

provide a grapple or over-shot device indicated in its entirety by the numeral 25, comprising a metal body having a cable or like connection engaging the upper end 5 thereof, as indicated by the numeral 26, while a downwardly opening pocket 27 is formed in the under side thereof corresponding in size and shape to the upper extended portion of the rod 10 and adapted 10 to snugly receive the same therein. Normally inwardly thrusted bolts or pins 28 are slidably mounted in horizontally arranged openings or pockets formed in the body of the over-shot 25 and receive there- 15 about expansible coiled springs 29 serving to impart such inward thrust thereto; the inner ends of the pins or bolts being pivotally connected to levers 30 having their free extremities normally arranged in vertically disposed ways 31 formed at diametrically opposite points in the lower or under side of the under-shot 25 in proximity to its outer portions. In this connection, it 20 is to be noted that the vertical ways 31 are provided with laterally extending branch openings accessible from the exterior portion of the over shot 25. In consequence, with the insertion of a suitable implement through these laterally extending branch 25 openings into the vertical ways 31, the levers 30 may be engaged and moved inwardly so as to effect retraction of the slideable bolts 28 against tension of their respective expansible coiled springs 29 in order that the 30 over shot may be disconnected from the upper end of the rod 10 and the drill thus released.

The slide bar or rod 7 which extends downwardly into the enlarged portion 5 of the longitudinal way is provided with a flattened portion or plate 32 of a width corresponding to the width of such enlarged portion 5 of the way and capable of being moved vertically therein, at times. 40 Upon the opposite faces of this plate 32 and arranged in proximity to the opposite sides or marginal portions thereof are series of spaced tapered ribs generally indicated by the numeral 33, and between these ribs there 45 are arranged screw receiving openings 34.

Link carrying or securing bars 35 are provided and as shown in the Figure 7 have transversely disposed pockets or recesses 36 formed therein and arranged in spaced relation corresponding to the arrangement of the tapered ribs 33 carried upon the opposite faces of the plate 32. Thus, these bars 55 are adapted to be engaged with the opposite faces of the plate 32 at points adjacent the opposite sides of the same, whereupon the tapered transverse pockets or recesses 36 will fit over the tapered ribs 33 and thus form a connection as between the plate 32 and the several bars 35. Inter- 60 nally, screw threaded openings 37 are

formed in the several link carrying bars 35 and are arranged complementally to the screw receiving openings 34 in the plate 32, whereby set screws 38 may be first passed through said openings 34 and then engaged 70 with the threads of the adjacent openings 37 whereby the link carrying bars 35 will be securely joined to the opposite faces of the plate 32 in the manner indicated in the Figure 6. 75

Cutter or reamer carrying links 39 are received in pockets 40 formed in the link carrying bar 35 and opening onto the inner sides or marginal portions of the same, as is also shown in the Figure 6; these links 80 having eyelets formed in certain of their ends adapted, when inserted in the pockets 40, to be aligned with bearing pin openings 41 also formed in the link carrying bars 35 whereby pivot pins may be passed through the same and through said eyelets of the links, as indicated by the numeral 42, in order that pivotal connection as between the several link carrying bars and their respective links 39 may be effected. These links 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 4 T-shaped ribs 49 formed upon their lower portions whereby they may be slidably introduced into correspondingly formed grooves occurring at the opposite ends of the windows 6 and in the adjacent portions of the lower part of the drill body 3. Thus, it will be seen that with outward sliding movement of the slide rod 7 carrying the plate 32 against tension of the expansible coiled 5 spring 12, pivotal movement of the links 39 upon their bearing pins 42 and 46 will be permitted and in consequence, the cutters 44 will be moved inwardly towards each other, riding over the inclined bearing surfaces 10 of the guide pieces 48 until they have been entirely removed from the windows 6. When so positioned, it will be understood that the lower portion of the drill body 1 may be then moved upwardly through the 15 open lower end of the drill stem 13 in order that the drill may be removed from the bore for repairs or inspection, as may be required. However, when the drill is again lowered into the drill stem 13, the lower portion 20 thereof will extend from the lower open end of said stem, as shown in the Figure 3, and the expansible coiled spring 12 will function to cause downward sliding movement of the bar 7 carrying the plate 32, 25 thereby permitting further pivotal movement of the connecting links 39 in order that the oppositely disposed and similarly moving cutters 44 may be passed through the windows 6 of the drill body and extended, as shown. When in these extended 30 positions, the cutters 44 will function, with rotation of the drill stem 13, to carry out the desired boring or drilling operation.

To facilitate inter-changing of the cutters 40 or reamers and their connection with the eyelet carrying end 43 of the links 39, the windows 6 formed in the drill body are of widths greater than said cutters or reamers. Thus, the particular devices to be connected 45 to the drill may be readily engaged with the eyelet carrying ends 43 of the links 39, whereupon reducer plates 50 are moved into that space occurring between one side of each of the windows 6 and the adjacent side 50 of the particular cutter or reamer received therein; these plates 50 carrying dove-tailed shaped ribs 51 upon one side thereof adapted to be engaged in correspondingly formed 55 grooves formed in the adjacent side of each of the windows 6 whereby to afford positive connection of such reducer plates with the drill body. Furthermore, to prevent sliding displacement of the reducer plates 50 with respect to the windows 6, locking screws 52 60 are adapted to be passed through openings formed in the dove-tailed shaped ribs 51 into engagement with screw threaded openings formed in adjacent portions of said drill body.

65 It is desirable that the drill be provided

with positive means for locking the cutters or reamers in their distended drilling position, and to effect this, I slidably arrange in horizontal ways formed adjacent the hexagonal upper portion 2 of the drill body 70 1, oppositely disposed locking bolts or pins 53, arranging expansible coiled springs 54 within such ways and about the adjacent portions of the pins whereby to normally exert inward thrusts to the same. Levers 75 55 are mounted into pockets or recesses 56 formed in adjacent portions of the drill body and are pivotally connected to the outer ends of the several bolts 53, as indicated at 57; these levers 55 being adapted to 80 be normally distended to those positions as shown in the Figure 3. Keepers or pockets are formed in the corresponding portions of the drill rod 7 and in consequence, with downward movement of such drill rod under influence of the expansible coiled spring 12, such keepers or pockets will become aligned with the inner extended end of the oppositely disposed bolt 53 and will be engaged thereby. Hence, the slide rod 7 will be 90 locked in its lowermost position and in consequence, inward movement of the cutters 44 or reamers 45 connected to the links 39 will be prevented. However, when it is desired to remove the drill from the drill stem 13, 95 it will be seen that with disengagement of the locking bolts or pins 14 from their respective keepers or pockets 19, upward movement of the drill body through the drill stem 13 will be permitted and the outwardly 100 extended levers 55 upon passing through the lower open end of such drill stem will be caused to move inwardly and during such inward movement will impart outward pulls to their respective slidably sprung pressed 105 bolts or locking pins 53, thereby disengaging the inner ends from such pins from their respective keepers in the slide rod 7 and permitting the rod to be moved upwardly, whereupon by reason of the pivotal connection of the cutters or reamers to the links 39 to the plate 32, such cutters or reamers will be caused to be drawn inwardly towards each other until they have been completely withdrawn from their extended positions 115 and will not interfere with elevation of the lower portion of the drill body from the lower open end of the drill stem 13.

A drill head 58 is provided the drill and carries thereon a screw threaded extension 120 or nipple 59 adapted to be turned into engagement with a downwardly opening screw threaded pocket formed in the lower end of the lower portion 3 of the drill 1. This drill head is provided with rotatable cutters indicated by the numeral 60, which, as will be noted, are arranged in positions whereby the drill when engaged with the matter to be bored or drilled, will readily enter the same.

The cutters 60 comprise rollers having cutter serrations formed upon their peripheral portions, while bearing openings 61 are formed therein and are adapted to receive the shank portions of bearing pins 62 therethrough, such bearing pins being provided with enlarged heads 63 having circular tapered beads 64 formed upon their inwardly disposed bevelled sides and adapted 10 to enter correspondingly formed grooves 65 formed in the adjacent sides of said cutters 60. Furthermore, the opposite sides of the cutters 60 are formed with circular tapered grooves 65', corresponding to the grooves 65, 15 whereby a circular and tapered rib 66 formed upon the inner bevelled side of a circular plate 67 is secured to adjacent portions of the drill head 58 through the medium of screws 68, engaged therein. Because 20 of this particular construction, it will be understood that the opposite sides of the bearing opening 61 of the various cutters 60 will be positively closed and in consequence, the passage of sand, grit, or dirt 25 into engagement with the anti-frictional bearing devices of such cutters will be prevented and therefore, premature deterioration of the cutters will be avoided.

The cutters 44, as shown, have elongated 30 rotatable cutters 69 rotatably engaged with the outer side portions thereof, whereas the lower portions of the same are stepped and have other cutters 70 rotatably connected thereto by means of bearing pins or devices 25 corresponding to the element indicated hereinbefore by the numerals 62, 63 and 67. Thus, the passage of abrasive substances into engagement with the anti-frictional bearings of the cutters 70 will be avoided.

40 The reamers 45 are adapted to be formed with chamfered cutting edges 71, while the lower and under portions of the same are formed, as indicated at 72, whereby they will effectually cut through mud and similar matter and at the same time, will plaster or smooth the walls of the bore being made.

It is to be understood that various forms 50 of drill heads may be connected to the lower end of the drill body 1, such as conditions or preference may dictate and in the majority of these drill heads, it is preferable to supply the same with a cooling fluid, such as water, whereby that heat generated by friction during rotation of the drill will 55 be kept at minimum. To carry out this object, cooling fluid conveying and discharging ways 73 are formed within and extended longitudinally of the drill 1, opening onto the upper side thereof, as shown in 60 the Figure 4, while the lower ends of the same converge, as is indicated by the numeral 73', and are adapted to communicate with fluid receiving and discharging ways formed in the particular drill head employed in connection with the drill. Thus,

water will be discharged onto the drill head adjacent its various cutters and by consequence, excessive heat which is frequently caused by friction resulting from rotation of the drill will be kept at minimum. 70

In operation of my improved drill, the drill is lowered into the drill stem to that position as shown in the Figure 3, whereat the hexagonal upper portion 2 thereof will be snugly engaged with the correspondingly 75 formed lower end of the drill stem 13 and thus, a driving connection as between the two will be established. When the lower portion 3 of the drill body 1 has passed through the lower open end of the drill stem 13, the slide rod 7 will immediately move to its lowermost position under influence of the expansible coiled spring 12, whereupon the cutters or reamers connected to the links 39 will be moved laterally to their extended positions through the windows 6. When the slide rod 7 has reached its lowermost position, the slidable spring pressed locking bolts or pins 53 will immediately 80 engage in their respective keepers in such rod and in consequence, will serve to prevent any further upward movement thereof or inward movement of the cutters or reamers connected to the links 39. Hence, 85 proper functioning of the cutters or reamers during rotation of the drill will be ensured. Simultaneously with lowering of the hexagonal upper portion 2 of the drill into the lower end of the drill stem, it will be understood that the outwardly thrust slidable 90 locking bolts or pins 14 will be engaged with their respective keepers 9 as will the rounded heads of the locking pins 20 and therefore, undesirable upward movement of the drill with relation to the drill stem 13 100 105 will be prevented.

When it is desired to remove the drill from the drill stem 1, the over-shot device 25 is lowered into the stem 13 until it engages with the upper end of the drill 1; the 110 spring pressed slidable locking pins 28 engaging with the notched portions 11 formed in the upper end of the rod 10 and effecting positive connection as between said over-shot and the drill 1. Simultaneously, the 115 vertically disposed pins 22 will be forced downwardly so that the inclined portions of their respective shoes 23 will engage with the corresponding levers 17 connected to the locking bolts or pins 14 and move the same 120 inwardly, thus effecting retraction of said locking bolts or pins 14 and disengaging the same from their respective keepers or pockets 19. At this time, an upward pull is imparted to the cable 26 connected to the 125 over-shot device 25, whereupon the rounded head of the spring pressed pins 20 will be automatically disengaged from their respective pockets or keepers in the inner side walls of the drill stem 13 and the drill is 130

then elevated. During movement of the levers 55 through the open lower end of the drill stem 13, the same will, of course, be moved inwardly, thus disengaging their locking bolts or pins 53 from the slide rod 7 and permitting upward movement of said slide rod against the tension of the expandable coiled spring 12, whereby to permit of pivotal movement of the link 35 and 10 the resultant retraction of the cutters or reamers connected to the same so that the lower portion of the drill body may be moved through the open lower end of the drill stem 13 without interference. To dis- 15 engage the drill from the overshot device 25, subsequent to removal of the same from the bore, it is only necessary to insert a suitable implement in the laterally extending branch openings of the openings 31 whereby to 20 cause inward movement of the levers 30 with the consequent retraction of their respective locking pins or bolts 28.

Manifestly, the construction shown is capable of considerable modification and such 25 modification as is within the scope of my claims, I consider within the spirit of my invention.

I claim:

1. A drill comprising a body portion having an upwardly opening longitudinally disposed way therein, the lower portion of which is enlarged and formed with oppositely arranged windows, a rod slidably received in said way carrying a flattened plate 35 on its lower end, cutters pivotally connected to said plate and adapted, at times, to be extended through said windows, means for automatically locking said rod against sliding movement and operable to release the 40 same upon upward movement of the drill, and a bit connected to the lower end of the drill.

2. A drill comprising a body portion having an upwardly opening longitudinally disposed way therein, the lower portion of which is enlarged and formed with oppositely arranged windows, a rod slidably received in said way carrying a flattened plate on its lower end, cutters movably connected 45 to said plate adapted, at times, to be extended in opposite directions through said windows, means for automatically locking the cutters against inward movement subsequently to movement of the same to extended 50 positions and operable to release the cutter upon upward movement of the drill, and a bit connected to the lower end of said drill.

3. A drill comprising a body portion having an upwardly opening longitudinally disposed way therein, the lower portion of which is enlarged and formed with oppositely arranged windows, a rod slidably received in said way carrying a flattened plate 60 on its lower end, oppositely moveable cutters pivotally connected to said plate and

adapted, at times, to be extended through said windows, means for automatically locking said cutters against movement subsequently to arrangement of the same through said windows and operable to release the 70 cutters upon upward movement of the drill, and a bit connected to the lower end of said drill.

4. A drill comprising a body portion having an upwardly opening longitudinally disposed way therein, the lower portion of which is enlarged and formed with oppositely arranged windows, a rod slidably received in said way carrying a flattened plate 75 on its lower end, means for normally exerting a downward thrust and pressure upon said rod, cutters pivotally connected to said plate and moveable in opposite directions whereby they may be extended through said windows, at times, means for automatically locking said rod against sliding movement and operable to release the same upon upward movement of the drill, and a bit connected to the lower end of said drill.

5. A drill comprising a body portion having an upwardly opening longitudinally disposed way therein, the lower portion of which is enlarged and formed with oppositely arranged windows, a rod slidably received in said way carrying a flattened plate 90 on its lower end, cutters having their upper and lower portions bevelled pivotally connected to said plate and adapted, at times, to be extended through said windows by movement in opposite directions, means for automatically locking said cutters against movement subsequently to their movement through said windows but operable to release the same upon upward movement of the 95 drill, and a bit connected to the lower end of said drill.

6. A drill comprising a body portion having an upwardly opening longitudinally disposed way therein, the lower portion of which is enlarged and formed with oppositely arranged windows, a rod slidably received in said way carrying a flattened plate 100 on its lower end, oppositely disposed and moving cutters pivotally connected to the opposite side portions of said plate and arranged adjacent its opposite faces, said cutters adapted, at times, to be extended through said windows, means for automatically locking said cutters in their positions when extended through said windows, but 105 operable to release the same upon upward movement of the drill, and a bit connected to the lower end of said drill.

7. A drill comprising a body portion having an upwardly opening longitudinally disposed way therein, the lower portion of which is enlarged and formed with oppositely disposed windows, a rod slidably received in said way carrying a flattened plate 110 on its lower end, bars secured to the opposite 115

- faces of said plate adjacent its opposite sides, links pivotally connected to said bars and disposed in opposite directions parallel to the opposite faces of said plate, cutters pivotally connected to the free ends of said links and movable, at times, through said windows, means for locking said cutters in certain positions against inward movement, but operable to release the same whereby to permit 10 inward movement thereof with upward movement of the drill, and a bit connected to the lower end of said drill.
8. A drill comprising a body portion having an upwardly opening longitudinally disposed way therein, the lower portion of which is enlarged and formed with oppositely disposed windows, a rod slidably received in said way carrying a flattened plate on its lower end, cutters pivotally connected 20 to the opposite sides and faces of said plate and adapted, at times, to be extended through said windows, and automatically operable means for locking said cutters against inward movement subsequently to 25 their extension through said windows but operable with upward movement of the drill to release said cutters and permit such inward movement of the same.
9. A drill comprising a body portion having an upwardly opening longitudinally disposed way therein, the lower portion of which is enlarged and formed with oppositely arranged windows, a spring pressed rod slidably received in said way carrying 30 a flattened plate on its lower end, oppositely moving cutters pivotally connected to the opposite sides and faces of said flattened plate and adapted, at times, to be extended through said windows, inwardly thrust 35 slidable locking pins arranged in a portion of the drill body engageable with said rod, at times, to lock the same against sliding movement, and means carried upon the outer ends of said locking pins engageable with a 40 drill stem upon upward movement of the drill therethrough whereby to move said pins to their released positions.
10. A drill comprising a body portion having an upwardly opening longitudinally disposed way therein, the lower portion of which is enlarged and formed with oppositely disposed windows, a rod slidably received in said way carrying a flattened plate on its lower end, bars disposed longitudinally of said plate arranged upon its opposite faces and adjacent its opposite sides, oppositely disposed pairs of links pivotally connected to said bars, cutters pivotally connected to the free ends of said links and adapted, at times, to be extended through said windows, slidable spring pressed locking pins arranged in ways formed in said drill body and engageable, at times, with said rod whereby to prevent sliding movement of the same in said way, means car- 50
- ried upon the outer ends of said pins engageable with a drill stem casing upon upward movement of the drill whereby to move said locking pins to their retracted position and disengage said rod, and a drill bit carried upon the lower end of the drill.
11. A drill comprising a body portion, cutters movably carried by said drill and adapted to be extended therefrom, at times, and normally extended automatic locking pins carried upon the upper portion of said drill engageable with portions of the inner side of a drill stem whereby to lock said drill with relation to the stem, and means for effecting disconnection of said pins from the drill stem, at other times.
12. A drill comprising a body portion, cutters movably carried within said drill and adapted to be extended outwardly therefrom, at times, slidable spring pressed locking pins carried in the upper portion of said drill adapted to be automatically moved outwardly into engagement with portions of the inner walls of a drill stem, levers carried on the inner ends of said pins, and vertically disposed spring pressed pins carried by the drill and extending from the upper end thereof, adapted at times, to be depressed and to engage said levers of the first pins whereby to move the latter to retracted positions and disengaged from said drill stem.
13. A drill comprising a body portion carrying movable cutters therein adapted to be extended from the peripheral portions of the same, at times, means for automatically locking said cutters in their extended positions but operable to release the same upon upward movement of the drill in a drill stem, spring pressed slidable oppositely disposed locking pins carried in the upper portion of said drill body adapted to be engaged with portions of the inner walls of the drill stem whereby to connect said body to said stem, levers pivotally connected to the inner ends of said locking pins, and vertically disposed pins carried in the upper portion of said body extending upwardly from the same adapted, at times, to be engaged with said levers whereby to retract said first pin and disengage the same from said inner walls of the drill stem.
14. A drill comprising a body portion having an upwardly opening longitudinally disposed way therein, the lower portion of which is enlarged and formed with oppositely arranged windows, a spring pressed rod slidably received in said way carrying a flattened plate on its lower portion, oppositely movable cutters arranged adjacent the opposite faces and opposite sides of said plate pivotally connected to the same and adapted to be extended, at times, through said windows, spring pressed slidable locking pins carried by the drill body engage- 100

- 115
- 120
- 125
- 130

- able, at times, with portions of said rod, levers pivotally connected to the outer ends of said pins and adapted to extend beyond the adjacent sides of the drill body whereby to be engaged with the lower end of a drill stem upon upward movement of the drill body therethrough, other spring pressed slidable locking pins arranged in ways in the upper portion of said drill body engageable with portions of the inner walls of the drill stem whereby to effect connection between said body and stem, levers pivotally connected to the inner ends of said second mentioned locking pins, vertically disposed pins slidably arranged in the upper portion of said drill body extending upwardly beyond the same and adapted, at times, to be moved into engagement with the levers of said second mentioned locking pins whereby to retract the same, spring pressed supplemental locking pins slidably arranged in the upper portion of said drill body also engageable with portions of the inner wall of said drill stem, and a drill bit connected to the lower end of said drill body.
15. A drill comprising a body portion, oppositely moveable cutters pivotally connected to and arranged in the lower portion of said drill body adapted to be extended beyond the same, at times, the upper portion of said drill body being hexagonal in cross section and snugly receivable in the lower portion of a drill stem, means for automatically effecting connection between said drill stem and hexagonal portion of the drill body but adapted, at other times, to be automatically disengaged therefrom, and other automatic means for securing said cutters in their extended positions, at times, but operable at other times to permit movement of the same to their innermost positions within the drill body, and a bit carried upon the lower end of said drill body.

In witness whereof I have hereunto set my hand.

DONALD HENRY MITCHELL.
